Des. 235,886
Patented July 15, 1975

235,886

RELIGIOUS MEDALLION

Norman Kirk, 9 Rosedale Ave.,
Montclair, N.J. 07042

Filed July 5, 1973, Ser. No. 376,798

Term of patent 14 years

Int. Cl. D11—02

U.S. Cl. D29—11 C

FIG. 1 is a front elevational view of a religious medallion showing my new design, the back of the chain being the same in appearance as the front and the rest of the back of the medallion without any design appearing thereon.

FIG. 2 is an edge elevational view.

I claim:

The ornamental design for a religious medallion, as shown and described.
